(57) CLAIM

The ornamental design for an exercise cover towel, as shown and described.

DESCRIPTION

FIG. 1 is a front, top and left side perspective view of the exercise cover towel.

FIG. 2 is a front, top, left side perspective view thereof;

FIG. 3 is a top plan view of the exercise cover towel.

FIG. 4 is a bottom plan view of the exercise cover towel.

FIG. 5 is a front elevational view thereof.

FIG. 6 is a rear elevational view thereof.

FIG. 7 is a left side view thereof; and,

FIG. 8 is a right-side view thereof.

The broken lines showing handlebars support in FIG. 2 are for the purpose of illustrating environment and form no part of the claimed design.
